UNITED STATES PATENT OFFICE.

EMILE GAUTHIER AND CAMILLE RODRIGUES-ELY, OF PARIS, FRANCE.

APPARATUS FOR PERFORATING AND CUTTING METALS.

No. 874,666.

Specification of Letters Patent.

Patented Dec. 24, 1907.

Application filed April 5, 1907. Serial No. 366,648.

To all whom it may concern:

Be it known that we, EMILE GAUTHIER and CAMILLE RODRIGUES-ELY, citizens of France, residing at Paris, in the Republic of France, have invented certain new and useful Improvements in Apparatus for Perforating and Cutting Metals, of which the following is a full, clear, and exact description.

The subject of the present invention is a device for cutting and perforating metals by means of a stream of gas under pressure.

The process to which the apparatus relates consists in leading the combustible, serving to heat the place of work in a plurality of streams to the place of work.

With the apparatus hitherto employed the leading of the combustible took place through a channel concentric with the conduits for the oxidizing gas, so that the two kinds of gas (combustible and oxygen) serving to cut or perforate the metal combined in large arcs on the piece of work. With the apparatus constituting the present invention on the other hand, the quantities of gas necessary for the heating is lead in several independent streams to the work for the purpose of increasing the production of heat, and to bring about a more intense heating of the piece of work.

A further novel feature of the present invention consists in arranging the outlets for the gas and combustible in different places or in arranging the outlet for the current of gas as near as possible to the place of work. This division of the current of gas has the great advantage that its leading can be regulated according to the particular purpose in view, namely either by regulating only the quantity of combustible gas streaming through at one side of the current of gas under pressure by choosing a corresponding diameter, or in leading the combustible only at one of the gas outlets.

The device embodying our invention consists of a rose or mouth-piece in which suitably arranged outlet openings are provided around the outlet for the current of gas. Any suitable mixture of gas may be adopted, applicants use with advantage a combination of acetylene and oxygen.

In the accompanying drawing several modified forms of construction are shown:

Figure 1 is a longitudinal section through the mouth piece. Fig. 2 is a face view of the mouth-piece. Fig. 3 is a cross section of a mouth-piece with outlet openings arranged

in different planes. Fig. 4 is a view with outlet openings of different sizes. Fig. 5 is a view of a mouth-piece outlet openings for the gas mixture arranged at one side and Fig. 6 represents how the work is carried out.

The mouth-piece designated *g* in Fig. 1 is fed by two conduits of which one *a*, leads the combustible, serving to heat the place of work, which consists of a gas mixture mixed with oxygen, while the other *b* leads the oxygen under high pressure for fusing the metal, which is cut through by the high pressure gas. The oxygen leaves the mouth-piece through the opening *e* while the gas mixture goes through the openings *d* and is ignited.

In the form of construction shown in Fig. 1 the outlet openings for the combustible and gas current (oxygen) are arranged in one plane. The piece of metal subjected to the operation of the device is heated up opposite the outlet openings *d*, and it is sufficient to heat up the particular spot to a red heat for the purpose of producing by the subsequent action of the stream of oxygen under high pressure, openings (perforations) in the piece of the metal. If now the device is moved forward on the line *x*—*x* for instance in the direction of the arrow, then the perforation is continued in the line *x*—*x* and the metal cut in two.

The heat necessary for carrying out the process is delivered by the combustible gases and partly by the metal itself, which latter through the combustible gas mixed with oxygen and on account of the current of the gas under high pressure is strongly heated up. The heat liberated by the combustion of the metal diminishes the quantity of heat to be applied by the hot gases.

Experience shows that the relative positions of the openings *d* and *e* is of considerable importance for the action produced, not only in regard to the wear and tear of the parts of the device in the neighborhood of the heated metal, but also in respect to the rapidity of the working process, the beauty of the cut and economy in the consumption of gas.

A further improvement consists in arranging the outlet for the stream of gas in a lower plane than the heating jet outlet, that is to say nearer to the place of work than that of the outlet openings for the combustible. This form of construction is shown in Figs. 3, 5 and 6 in which the mouth-piece is provided with a projection *h* in which the

oxidizing gas outlet channel e is prolonged, while the combustible gases leave the mouth-piece through the openings d . The projection h can be replaced, and can be made of material capable of resisting heat. The enlargement of the combustible outlet openings on the side toward which the apparatus is shifted, is of importance for the practical operation of the apparatus.

10 The device having enlarged openings on one side of the oxidizing jet is shown in Fig. 4, and the arrangement is such that a shifting of the tool towards the left in the direction of the arrow on line $Y-Y$ is intended.

15 In this construction, accordingly, the outlet openings d^2 in the working direction of the tool, namely on the left side of the gas outlet, e^1 have a greater diameter than those on the right side. Finally the invention can

20 be so modified, that the outlet openings for the gas will be located only at one side of the current of oxidizing gas. (Fig. 5.)

The number, the diameter and the position of the combustible gas openings d^3 and 25 the position of the oxidizing gas opening e^1 in Fig. 5 can be chosen according to the properties of the particular metal dealt with especially according to the form of the line of section.

30 I claim:

1. In an apparatus for cutting metals by means of a heating jet, and an oxidizing jet, a mouth piece having an oxidizing gas

current outlet and several combustible gas outlet openings arranged and adapted to 35 discharge combustible gas in streams substantially parallel to the stream of oxidizing gas substantially as and for the purpose set forth.

2. In an apparatus for cutting metals by 40 means of a heating jet, and an oxidizing jet, a mouth-piece having outlet openings for the current of oxidizing gas and combustible gas in different planes respectively, all said openings being formed and adapted to direct streams of gas in parallel lines.

3. In an apparatus for cutting metals by heating and oxidizing jets, a mouth-piece having an oxidizing gas outlet and a plurality of combustible outlet openings of different diameters, substantially as and for the purpose set forth.

4. In an apparatus for cutting metals by heating and oxidizing jets, a mouth-piece having an oxidizing gas outlet and having a 55 plurality of combustible gas outlet openings only at one side of the oxidizing gas current outlet, substantially as and for the purpose set forth.

In witness whereof, we subscribe our signatures in presence of two witnesses.

E. GAUTHIER.

C. RODRIGUES-ELY.
